[57] CLAIM

We claim the ornamental design for a bread producing machine, as shown and described.

DESCRIPTION

FIG. 1 is a top, front, and right side perspective view of a bread producing machine showing our new design;
FIG. 2 is a front elevation view of our new design;
FIG. 3 is a right side elevation view thereof;
FIG. 4 is a left side elevation view thereof;
FIG. 5 is a rear side elevation view thereof;
FIG. 6 is a top elevation view thereof; and,
FIG. 7 is a bottom plan view thereof.
